CLAIM

The ornamental design for an electrical plug with intergral
overload protection, as shown and described.

DESCRIPTION

FIG. 1 is a right side elevational view of an electrical plug
with integral overload protection, illustrating my new design
therefor, it being understood that the left side elevational
view thereof is identical;

FIG. 2 is a rear elevational view of the plug of FIG. 1;

FIG. 3 is a front elevational view of the plug of FIG. 1;

FIG. 4 is a top plan view of the plug of FIG. 1;

FIG. 5 is a bottom plan view of the plug of FIG. 1;

FIG. 6 is a right side elevational view of an electricil plug
with intergral overload protection illustrating a second
embodiment of my new design, the left side elevational view
being identical;

FIG. 7 is a rear elevational view of the plug of FIG. 6;

FIG. 8 is a front elevational view of the plug of FIG. 6;

FIG. 9 is a top plan view of the plug of FIG. 6; and,

FIG. 10 is a bottom plan view of the plug of FIG. 6.
